US0D1106815S

(12) **United States Design Patent** (10) **Patent No.:** **US D1,106,815 S**
(45) **Date of Patent:** **** Dec. 23, 2025**

(54) **ONE-CELL BEVERAGE BOX**

- (71) Applicant: **Pratt Corrugated Holdings, Inc.**,
Brookhaven, GA (US)
- (72) Inventors: **Shifeng Chen**, Newport News, VA
(US); **Greg Sollie**, Sharpsburg, GA
(US); **Jamie Waltermire**, Peachtree
City, GA (US)
- (73) Assignee: **Pratt Corrugated Holdings, Inc.**,
Brookhaven, GA (US)
- (**) Term: **15 Years**
- (21) Appl. No.: **29/928,460**
- (22) Filed: **Feb. 12, 2024**

Related U.S. Application Data

- (63) Continuation of application No. 29/753,414, filed on
Sep. 30, 2020, now Pat. No. Des. 1,026,667.

(57) **CLAIM**

The ornamental design for a one-cell beverage box, as
shown and described.

DESCRIPTION

FIG. 1 is a rear perspective view of the claimed design
shown with a top portion of the one-cell beverage box
positioned in an open configuration and a telescoping
portion of the one-cell beverage box positioned in a telescoped
configuration.

FIG. 2 is a rear elevation view thereof.

FIG. 3 is a front elevation view thereof.

FIG. 4 is a right-side elevation view thereof.

FIG. 5 is a left-side elevation view thereof.

FIG. 6 is a top plan view thereof.

FIG. 7 is a bottom plan view thereof.

FIG. 8 is a plan view of a box blank that can be assembled
to form the one-cell beverage box of FIG. 1.

FIG. 9 is a front plan view of the one-cell beverage box
shown in a collapsed configuration; and,

FIG. 10 is a rear plan view of the one-cell beverage box
shown in the collapsed configuration.

Those features shown in broken lines form no part of the
claimed design.
